UNITED STATES PATENT OFFICE.

GEORGE PRESCOTT FULLER, OF LA SALLE, NEW YORK, ASSIGNOR, BY MESNE ASSIGNMENTS, TO EDWARD MICHAEL, FRANK R. COLLINS, AND FRANK J. TONE, CONSTITUTING BONDHOLDERS' PROTECTIVE COMMITTEE OF ELECTROLYTIC HOLDING COMPANY, INC.

PUMP FOR CORROSIVE LIQUIDS.

Application filed October 8, 1926, Serial No. 140,274. Renewed November 3, 1928.

In the electrolytic production of iron it becomes necessary to circulate considerable quantities of ferrous chloride solution, with which there may also be admixed ferrous chloride and free acids, at a temperature of around 80 degrees centigrade. Such a solution at this temperature is highly corrosive and erosive of all materials from which it has been hitherto possible to construct a centrifugal pump or pump of other type as ordinarily designed. Practically the only material which is capable of meeting the requirements of such service, that is, effectively resists the corrosive or erosive action of such a solution at the temperatures encountered in service, is cementitious material such as cement or concrete which after the forming or molding thereof and thorough setting and drying has been impregnated with suitable material such as sulphur to close the pores and keep the liquid from reaching embedded reinforcing material. An important object of the invention is to provide a pump which will meet the required conditions. Other objects of this invention are to provide a pump design which will permit of the use of the material specified above in lieu of the materials which are ordinarily used in such mechanical structures, and a structure which will not require bearing surfaces of such material where there is any considerable pressure between the same and will also admit the use of reinforcing materials which have the requisite stiffness and tensile strength for the transmission of power for the operation of the pump.

Other objects and advantages will herein-after appear.

In the accompanying two sheets of drawings which form a part of this description,

Figure 1 is a vertical section through a centrifugal pump which embodies this invention on the line 1—1 of Fig. 2.

Figure 2 is an elevation of the pump with the cover to the casing removed and the impeller partly broken away.

Figure 3 is a front view of the split gland for the stuffing box.

Figure 4 is a side view of the same.

Figure 5 is a vertical section through the reinforcement for the impeller on the line V—V of Fig. 6, the concrete formed around the reinforcement being shown in dotted outline, and

Figure 6 is a central vertical section 55 through the impeller of Figure 5 and looking towards the left.

The pump comprises a casing of concrete in two parts one of which is the main body of the pump casing 10 with a stuffing box 11 formed therein, and the other of which is the cover plate 12. Sheets of expanded metal 13, 13 are embedded in the walls of the casing, nuts and bolts 14, 14 are embedded for attaching thereto an inlet pipe 15, and an outlet pipe 16, for bolting to the foundation, and for drawing up the split gland 17 for the stuffing box. Holes are left for through bolts 18, 18 by which the parts of the casing are held together, with a rubber gasket between. Plates 19, 19 of suitable material, such as steel, are placed on the sides of the casing for engagement by the nuts of the through bolts to distribute the strain.

Revolutionarily mounted within the casing is an impeller of reinforced concrete which comprises two parallel shrouds 20, 20 with blades 21, 21 cast between the shrouds, and a portion or sleeve 22 which enters the stuffing box in the casing. Annular sheets 23, 23 of expanded metal reinforce the shrouds. A steel shaft 24 passes through the sleeve, which provides a protecting layer of concrete for the portion of the shaft which enters the stuffing box from within the casing. A steel plate spider 25 is shrunk or otherwise secured on the end of the shaft and the spider is preferably extended to within an inch of the periphery by the corresponding annular sheet 23 of expanded metal 90 which is welded to the spider and is embedded in the corresponding shroud. Steel rods 26, 26 connect the sheets of expanded metal in the two shrouds, the ends of the rods being welded to the expanded metal. 95 Steel pins 27, 27 set in the shaft serve to support an expanded metal cylinder 28 which serves as a reinforcement for the sleeve.

In making the impeller, the shaft and the reinforcing parts are assembled and connected to one another, as by welding, and concrete is then formed around them as by casting or molding, to produce the shrouds, blades and sleeve. Holes 29, 29 are cored through the shrouds and blades to even up the pressure 105 on the two sides of the impeller and give it hydraulic balance and also to lighten its weight. The disks of expanded metal are

provided before assembling with any openings or holes which may be required. At the back of the impeller, there are provided four ribs 30, 30 to increase the centrifugal action on the liquid in the pump at the inner end of the stuffing box and thus maintain the pressure at this point slightly below the exterior pressure, thereby preventing leakage of the solution at this point. The concrete is of selected materials, carefully mixed and well tamped or compacted to insure uniformity and strength.

After the concrete has thoroughly set and dried the sleeve is ground to a true cylinder with a perfectly smooth surface. The exposed portions of the impeller are then smoothed off and it is carefully balanced by grinding and chipping the concrete from the sides of the shrouds. The balanced impeller and also the casing after thoroughly setting and drying are impregnated with molten sulphur which fills the pores, increases the tensile strength, protects the reinforcing elements from chemical attack and imparts a smooth surface so that the liquid will pass through the pump more freely. Such an impeller, it has been found, may be safely driven at a peripheral speed of 60 feet per second. The stuffing box is packed with any suitable material such as ordinary ring packing. A stream of water from a pipe 31 is directed into the stuffing box from the outside and serves as a lubricant and also to seal the opening, thereby preventing the sticking of air into the pump because of the difference between the exterior and the interior pressures.

The shaft is supported exterior to the pump casing by two bearings 32, 32, one of which is also a thrust bearing. The one which adjoins the pump may be close thereto but leaving sufficient room to withdraw the gland, which is split, free from the stuffing box to give access to the packing. These bearings support the shaft so that the stuffing box is not required to serve as a bearing. As it may be inconvenient to form the impeller on a shaft which is long enough to reach from the impeller through both bearings, use may be made of a short length of shafting with its end cast in the impeller and of an extension length of shafting 33 to run in the further

bearing and attached to the short length of shafting by a coupling 34. The outer end of this extension shafting is connected through a flanged coupling 35 to an electric motor or other driving mechanism.

It should be understood that the reinforcement of the concrete may consist of any suitable material, such as expanded or perforated metal.

It should also be understood that various changes may be made without departing from the true scope and spirit of the invention.

Having thus described my invention, I claim:

1. A centrifugal pump comprising a casing of concrete with a stuffing box therein, an impeller of reinforced concrete, and a metal shaft connected to the reinforcement in the impeller members, passing through the stuffing box and having a protecting layer of concrete on the portion which enters the stuffing box from within the casing.

2. In a centrifugal pump, an impeller comprising a metal spider, metallic reinforcing material including sheet material secured to said spider and cementitious material covering said spider and metallic reinforcing material to protect the same from liquid passing through the pump.

3. In a centrifugal pump, a casing, a revoluble member comprising a shaft and an impeller comprising a spider on the end of said shaft, reinforcing material arranged around said shaft adjacent the spider, reinforcing means attached to said spider to determine the general outline of said impeller, and resistant cementitious material applied about said shaft, spider and reinforcing material to form the exposed part of the impeller and a cylindrical member surrounding the shaft and adapted to fit an opening in the casing.

4. In a centrifugal pump, an impeller comprising a metal spider, metal reinforcing material, corrosive-resistant material surrounding said spider and forming a part adapted to be journaled in an opening in the pump casing, and a driving shaft extending into said part and fixed to the spider.

In witness whereof, I affix my signature.
GEORGE PRESCOTT FULLER.
